R. W. SCOTT,
KNIT FABRIC AND METHOD OF KNITTING THE SAME,
APPLICATION FILED SEPT. 7, 1915.

Patented July 4, 1916.

Attorneys.

UNITED STATES PATENT OFFICE.

ROBERT W. SCOTT, OF BOSTON, MASSACHUSETTS.

KNIT FABRIC AND METHOD OF KNITTING THE SAME.

1,189,744.

Specification of Letters Patent.

Patented July 4, 1916.

Application filed September 7, 1915. Serial No. 49,161.

To all whom it may concern:

Be it known that I, ROBERT W. SCOTT, a citizen of the United States, and resident of Boston, in the county of Suffolk and State of Massachusetts, have invented new and useful Improvements in Knit Fabrics and Methods of Knitting the Same, of which the following is a specification.

This invention relates to knit articles, such as stockings, or other knit apparel having an in-turned welt formed during manufacture, and to a method of making such articles in an improved manner by hand or machine to form a fold, turn or welt continuous with the body fabric at one end and fastened at or near the other end to the body fabric on the inner or back face of the body fabric by an improved knit structure, the welt having its face or wale side outside.

One object of the invention is to provide an improved structure at the place of fastening.

Other objects are to provide a mode of making such articles susceptible of being carried out on knitting machines, for instance circular knitting machines capable of producing seamless stockings, by automatic or by hand operations.

Another object of the invention is to so order the steps taken as to necessitate use of but one row or set of knitting needles.

In my Letters Patent No. 864,433 dated August 27, 1907, I have shown and described a stocking having an inturned welt and method of making the same in which the first step in the manufacture comprises forming a setting-up course taken alternately by knitting needles of two different series capable of being operated in directions at an angle to each other, and thereafter knitting upon one of said sets of needles fabric for the welt during retirement of the other set while still retaining the loops of the setting-up course; thereafter transferring the setting-up course or a course near it from the needles on which it had been retained to the needles employed in knitting the welt fabric, and then retiring the set of needles which so far had been employed only to take the setting-up course, and then completing the article. By this method the yarn of the setting-up course was called upon to bear the strains of the formation of said course, of the withholding of said course during the knitting of the welt, of the moving forward of the fabric, of replacement on

the knitting needles proper, of the transferring movement of the knitting needles, and thereafter the strain of withdrawal of that set of needles employed only for the purpose of forming and transferring the setting-up course. The welt so made necessarily was united to the body fabric by alternate loops of the setting-up course, or as many loops as there were needles for making said course. To practice my said method by machine required the provision of a second set of knitting needles within those employed for knitting the welt and the remainder of the article, and means for causing transfer from needle to needle. The necessary structure of a machine containing a second set of needles having such capacities is relatively expensive and complex. By my present invention I avoid the necessity for use of such devices, and avoid the strains produced in the fabric, and am able to provide a strong uniting structure which will not permit the welt to ravel, and which may have uniting loops at any desired frequency, such as every second, fourth or sixth needle-wale of the fabric.

In the accompanying drawings, Figure 1 is a series of diagrams illustrating steps in the manufacture; Fig. 2 is a sectional view of the welt or fold; Fig. 3 is a perspective view of certain instruments which may be used in practising the said method.

Referring now to Fig. 1, a series of bare needles viewed in plan is shown at I. Upon these needles an initial yarn 1, Diagram II, is wound in and out, passing behind recurrent needles. This step may be practised in any desired manner, for instance by retiring alternate needles n' (retired needles being shown in black) and then feeding a yarn to the remaining needles n'' . This initial yarn 1 is now enveloped by loops of second yarn 2, for instance by restoring the needles n'' taking the yarn 2 in the hooks of all of the needles and then casting off the yarn 1, to produce the selvage courses shown in Diagram III. Producing a starting selvage by the above indicated method is not new, except in its relation to the following steps, a fabric having such a selvage being the subject of my Letters Patent No. 1,045,621, dated November 26, 1912, the above described method of making such a fabric being in part the subject of my Letters Patent No. 13,752 reissued June 16, 1914. Machine devices for producing such a starting selvage

vage are shown and described in my Letters Patent No. 1,148,055 dated July 27, 1915, and one preferred instrument of manufacture for the article herein disclosed is a machine of the type disclosed in my said last-mentioned patent. Having formed upon the needles n' , n^2 such a starting selvage, the series of needles n' , n^2 may now become the instruments or places of formation of fabric having needle-wales at each of said needles, or any desired recurrent number less than the whole of them.

In order to make a structure for tying or uniting to a place in a following section of fabric the selvage edge so far described, I lay [Diagram IV] in the hooks of the needles n^2 only, a uniting course of yarn 3, which may if desired be a stronger or coarser than that of the remainder of the fabric, first having retired all of the needles n' to prevent their taking the yarn 3, and then cast off [Diagram V] upon loops y of yarn 3 all of the loops of course 2 of the selvage structure which were formed upon the needles n^2 . Needles n' still retain their loops of course 2 of the selvage.

Portions a of yarn 3 at the location of the needles n' are thus rendered available to be employed as uniting loops. After and during the steps represented in Diagrams IV and V such portions or bights a may be laid hold of by hand or by suitable implements preparatory to retaining them out of the way of the needles during knitting of the fabric for the welt W, Fig. 2. For instance, prior to laying course 3, and after retiring needles n' , implements h , Fig. 3, may be inserted in each space between a needle n^2 and the positions taken by needles n' when said needles n' are active, and in line with or near a normal position for the hooks of the needles, so that yarn 3 may be laid upon the implements h without forming enlarged bights a between needles n^2 . While I prefer to use implements h having notches k in their upper faces defining slender upwardly sloped points p , any instrument capable of detaining a loop and shedding it upon withdrawal without strain or distortion may be employed. As shown, implements h may be employed in pairs, their heads being symmetrically bent apart to space the points p at the proper distances to enter the spaces on each side of a needle n' .

The steps above described of laying the yarn 3, and knitting the loops y may take place while the implements h are positioned to receive the yarn 3 in line with the needles, as shown in Diagrams IV and V. With respect to the line of needles, knitting the loops y causes the yarn 3 to be thrown behind the needles between the needles n^2 and the implements h , and said implements can now be moved back through at least the distance measured by the course of loops [Dia-

gram VI] without altering the downward stress on bights a tending to retain bights a on the points p . When the implements h have been so moved, the needles n' are restored to operation, and a course 4 is knit at all of the needles, thus initiating needle-wales b at the loops of course 2 retained on needles n' , and needle-wales c at the loops of course 3 previously knit, as indicated in Diagram VII. Knitting now proceeds normally, the implements h retaining their hold on bights a of course 3, until enough fabric for the front and back walls of the welt W has been produced, for instance until course 100 has been formed. The needles n' are now again retired [Diagram VIII] and the implements h are moved forward into line with the needles, thus bringing the bights a of course 3 over the needles n' , whereupon the needles n' are again moved into position to enter the bights a . Implements h are now removed, points p slipping freely from and leaving bights a on needles n' in addition to the loops e of course 100 already on the needles n' . Course 101, Fig. 2, is now knit through the bights a and loops e , and the remainder of the article completed as usual.

During the knitting of the fabric for the welt W the selvage made up of courses 1 and 2, which is a relatively stiff structure, lies under the implements h in a position to restrain accidental movement of the forming fabric from lifting the bights a out of the notches k .

When, as explained above, the instrument of manufacture is a circular knitting machine, the needles n' , n^2 define a circle within which the implements h are radially placed. It is an observed tendency of the selvage structure to occupy when free a smaller circle than the needles on which it is formed. This phenomenon aids the retained bights a to follow the implements h when they are removed inward to leave enough clearance between their points and the needles to permit formation of the extent of fabric W.

While I have described the steps of forming the welt W as successive, it will be understood that two or more successive steps may be simultaneously performed at different parts of a series of needles, the operations proceeding along the series of needles, and following each other in the order stated at any given part of the series.

The fabric structure produced by the described steps may readily be made by hand operations without employing the instruments h . Having taken the steps illustrated in Diagrams I, II, and III, the needles n' may be rendered inoperative and course 3 fed to and knit by needles n^2 without inserting any implements at the location of the bights a , and the fabric for the welt formed by the steps above described. The selvage

of courses 1 and 2 and having near it the free bights *a* will now be a free end within or behind the needles. When enough fabric W is completed, the operator picks up by hand or any suitable hooked hand implement all or any desired part of the series of bights *a* and replaces them upon the needles, and then resumes knitting.

Without the selvage structure of courses 10 1 and 2 it would be impossible to secure against raveling the fabric W if uniting loops (such as those formed by bights *a*) were less frequent than at every other needle wale.

15 While I have described the implements *h* and shown them at each of the alternate needles *n'*, it will be understood that my invention contemplates employing any desired lesser number of such implements, for instance at the location of every other or every 20 fourth needle *n'*, only, and that the fabric formed by withholding and transferring recurrent bights *a* only of the course 3, or all of said bights *a*, has important advantages over 25 prior structures, for instance those of my said Patent No. 864,423. The tying or uniting course 3 being interknit in the needle wales *c* contains more yarn than an initial or setting-up course can contain without 30 looseness, and strains upon the welt fabric are distributed by this structure between the wales *c* of the welt fabric and the wales *b* in which the loops *a* are engaged, whereby there is less danger of breakage of the loops 35 at the point of fastening, either during manufacture or during use, than with the prior structure.

The selvage courses 1 and 2 serve to prevent raveling of the fabric containing the 40 uniting course to free the uniting course and thereby unfasten the welt, whether the uniting loops or bights *a* are in alternate wales or are more widely separated.

What I claim is:

45 1. A knit article having an integral in-turned welt comprising a selvage and having one of the structural knit courses of the welt fabric, constituting a knit uniting course, in engagement with both the selvage 50 and the body of the article at a point separated from the selvage by an extent of the fabric.

55 2. A knit fabric characterized by a selvage structure, and having one of the structural knit courses of the fabric, constituting a uniting course in engagement with said selvage structure in recurrent needle-wales and with the body fabric in other needle wales, an extent of fabric between the points 60 of engagement being turned face side out.

3. A stocking or the like having an integral in-turned welt attached near its be-

ginning edge to the back or inner face of the fabric of the body of the article by one of the structural knit courses of the fabric 65 thereof engaging a selvage structure at the beginning edge, said knit course having bights penetrated by loops of the body fabric.

4. A stocking or the like having an in- 70 integral in-turned welt attached near its beginning edge to the back or inner face of the fabric of the body of the article by one of the structural knit courses of the fabric engaging loops in alternate needle-wales of 75 a selvage structure at the beginning edge and having bights penetrated by loops of recurrent wales of the body fabric.

5. The method of knitting articles having in-turned welts comprising first forming a 80 selvage structure on a set of needles, then interknitting a uniting course therewith at recurrent loops only, and forming bights of said uniting course, thereafter replacing said bights on the needles, and then knitting 85 the remainder of the article.

6. The method of forming knit articles characterized by in-turned integral welts comprising the steps; forming a beginning selvage on a set of knitting needles; then 90 knitting a course at recurrent needles; thereafter withholding bights of said course from contact with the needles, and subsequently engaging said bights with the fabric. 95

7. The method of forming knit articles characterized by in-turning integral welts comprising the steps; forming a beginning selvage on a set of knitting needles; then 100 knitting a course at recurrent needles; thereafter withholding bights of said course from contact with the needles; and subsequently placing said bights on needles intervening between said recurrent needles.

8. The method of knitting articles hav- 105 ing in-turned welts comprising first forming a selvage structure on a set of needles, then forming a uniting course interknit at recurrent loops only, then detaining bights of said uniting course at a place removed 110 from and behind the needles, thereafter replacing said bights on the needles, and then knitting the remainder of the article.

9. The method of knitting on a single 115 series of needles comprising detaining bights of a knit course preceded by a selvage structure with which said course is interknit, holding said bights out of contact with any of the needles, and returning them to the needles after the production of fabric 120 for a welt.

Signed by me at Boston, Massachusetts this 31st day of August, 1915.

ROBERT W. SCOTT.
